CAN

Philip Meshberg, Bridgeport, Conn.

Application April 12, 1949, Serial No. 1,923

Term of patent 7 years

(Cl. D58—17)

To all whom it may concern:

Be it known that I, Philip Meshberg, a citizen of the United States, residing at Bridgeport, county of Fairfield and State of Connecticut, have invented a new, original, and ornamental Design for a Can, of which the following is specification, reference being had to the accompanying drawing, forming part hereof, in which:

Fig. 2 is a top plan view thereof.

The dominant features of my design reside in the portions shown in full lines.

I claim:

The ornamental design for a can, as shown and described.

PHILIP MESHBERG.
